GREETING CARD

Arthur Podmore, London, England

Application February 25, 1948, Serial No. 10,686
In Great Britain March 20, 1939Section 1, Public Law 690, August 8, 1946
Patent expires March 20, 1959

3 Claims. (Cl. 40—126)

1

The invention relates to greeting cards, advertising displays and like devices.

It is an object of the invention to provide means facilitating the construction of greeting cards and the like in a very efficient and inexpensive manner, said cards having a number of integral or attached picture sections or strips which lie flat on each other for storage or for transit and are adapted to be moved into spaced relationship in planes parallel to the plane of the card to form a composite picture.

It is another object of the invention to provide means enabling the creation of an unusual composite greeting, picture or similar display card which has only a relatively few parts or panels for producing three-dimensional impressions, said card consisting of a rear panel hingedly connected to an end panel (or panels), a picture section connected to the end panel (or panels) so as to be movable to a position away from the rear panel when the end panel or panels are moved at right angles or other suitable angle to the rear panel, and a cover panel hingedly connected to one end panel.

These and other objects of the invention will be pointed out in the following description and claims and illustrated in the accompanying drawings which disclose, by way of example, the principle of the invention and preferred modes which have been contemplated for applying said principle.

The accompanying drawings illustrate a Christmas card according to the invention;

Fig. 1 being a perspective view with the cover panel opened and the card in the erected condition;

Fig. 2 a view with the card collapsed and the cover panel in its covering position;

Fig. 3 a plan view of the card in the open or erected condition, and;

Fig. 4 a developed view showing a one piece blank for forming the Christmas card.

In carrying the invention into effect according to one convenient mode by way of example the Christmas or greeting card is formed from a suitable card material and comprises four panels, namely, a rear panel 5, two end panels 6 and 7 hingedly connected to the rear panel, and a cover panel 8 hingedly connected to the left hand end panel 6. The hinging may be effected by suitable scoring the material or hinge strips may be applied thereto.

When the card is in a collapsed or flat condition (see Fig. 2) the free edge 8a of the cover panel 8 is adapted to lie contiguous to the edge 7a of the right hand end panel 7.

2

Mounted on the inner face of the rear panel 5 or suitably impressed thereon, as by printing, is a section of a panoramic view. This section comprises the upper portion of the picture and occupies the full width of the panel extending from end panel 6 to the other end panel 7.

If desired, the picture may be continued on to the end panels.

Mounted forwardly of the rear panel and hingedly connected to the end panels is a pair of sections of the picture, namely an intermediate section 9 and a forward section 10. The intermediate section 9 comprises the central portion of the panoramic view, while the forward section 10 comprises the lower portion of the picture.

The intermediate section rises a suitable distance above the lower portion of the forward section according to the particular view being displayed. The forward and intermediate sections are cut out so that they form silhouettes of the portions of the view.

It will be appreciated that a suitable overlap will be provided between the intermediate section of the picture and the upper and lower picture portions, respectively, so that there are no gaps in the composite picture.

The forward section 10 of the picture is formed integral with a frame element 11 which is hinged in any suitable manner to the forward edges of the end panels 6 and 7. The frame portion 11 provides a window through which the upper portions of the composite picture are adapted to be viewed.

The upper marginal portion 7b of the right-hand panel 7 is adapted to be hinged, as by scoring the card at 7c, to the main part of the panel so that when the card is erected to display the view such marginal portion may be bent downwardly and inwardly to lie between the rear panel 5 and frame 11 to maintain the parts in the display position.

The cover panel may be arranged so that it may be readily removed from the end panel as by the provision of a row of perforations, or it may be arranged to form a permanent portion of the greeting card.

The outer surface of the cover panel 8 and preferably the outer surface of the end panel 7 are adapted to be utilized to receive a suitable picture as indicated in Fig. 2, and also suitable greeting inscription, while the inner surface of the cover panel may also be utilized for the printing of a greeting and also for the signature of the sender.

It is convenient to form the card from a single strip as indicated in the developed view, Fig. 4,

in which the cover panel, rear panel 5, combined frame and front section of the picture 11 and the intermediate section of the picture 9 are connected together by the end panels 6 and 7 and by the hinging flaps 12 and 13. The latter are adapted to be gummed to the end panels 6 and 7 (see Fig. 3) to hold the intermediate picture section 9 in correct relation with regard to the other parts of the card.

The various panels, sections and flaps are 10 preferably hinged to one another by suitable scoring of the card or by perforated lines 14.

Instead of forming the front portion of the picture in one with the frame element 11 such portion may comprise a further intermediate section, and in this case the frame could be provided with a transparent panel if desired. Where two intermediate sections of the picture are provided these will be displaced at suitable distances from the rear panel.

Instead of providing a pair of end panels, only one may be used, in which case the intermediate picture section at one end will be secured to such panel while at the other end or adjacent such end a hinge portion securing it to the rear panel is provided. This hinge portion may be provided with a bending part similar to 7b for maintaining the parts in the erected condition. With such an arrangement the front cover panel 8 will preferably be of a length equal to the combined lengths of the rear panel and one end panel so that the free edge of the extended cover panel reaches to the free edge of the rear panel when the card is collapsed.

Obviously an extended cover panel may be 35 employed with the form of card described with reference to the drawings, in which case the cover panel would extend over the end panel 7 when the card is collapsed.

While in the above described Christmas card 40 the forward and intermediate sections of the picture are such that the intermediate portion is exposed above the front portion and the rear portion is exposed above the intermediate portion, the position may be reversed according to the nature of the picture to be displayed.

As above described and as shown in the drawings the picture sections or strips lie parallel to the longitudinal dimension of the Christmas card. They may, however, lie transversely thereto, in which case the end panels will be hinged to the long edges of the rear panel so that the composite picture is viewed with said long edges vertical.

It will be appreciated, however, that the card 45 when erected need not be of rectangular shape, as it may be of square shape.

Moreover while it is preferred to employ a cover panel which when the card is collapsed covers the picture sections, such cover panel may be shorter so that the picture sections are partially exposed.

The card is adapted to be collapsed for postal purposes or transit and in use would normally be inserted within an envelope.

Having now particularly described and ascertained the nature of my said invention and in what manner the same is to be performed, I declare that what I claim is:

1. A collapsible picture card comprising a single sheet of material so arranged as to form a plurality of panels including two outer panels, an intermediate panel and opposite end panels, said outer panels forming a rear panel and a front panel, respectively, a fold connecting one end of one of said end panels with said rear panel, another fold connecting said rear panel with one end of the other end panel, a further fold connecting said front panel with the opposite end of said other end panel, said front panel being provided with a still further fold, a first extension 20 projecting from said still further fold along the inner face of said one end panel and in superposed position thereof and terminating at said intermediate panel which extends substantially parallel to said front panel and said rear panel, 25 said intermediate panel having a fold at each end thereof connecting said intermediate panel to said opposite end panels, a second extension of said intermediate panel extending along said other end panel at the inner face thereof toward 30 one of said outer panels, and means connecting said intermediate panel with both said end panels at both said extensions, said rear panel being provided with a pictorial design, said front panel and said intermediate panel being provided with cut-outs arranged in overlapping relation to each other and complementary to the pictorial design of said rear panel.

2. A collapsible picture card according to claim 1, wherein said one outer panel forms the rear panel.

3. A collapsible picture card according to claim 1, wherein the inner faces of said end panels and said extensions are provided with complementary parts of said pictorial design appearing on said rear panel.

ARTHUR PODMORE.
